UNITED STATES PATENT OFFICE.

WILLIAM B. GERE AND IRVING S. MERRELL, OF SYRACUSE, NEW YORK,
ASSIGNORS TO THE MERRELL-SOULE COMPANY, OF SAME PLACE.

EVAPORATOR.

SPECIFICATION forming part of Letters Patent No. 631,568, dated August 22, 1899.

Application filed September 13, 1898. Serial No. 690,837. (No model.)

To all whom it may concern:

Be it known that we, WILLIAM B. GERE and IRVING S. MERRELL, citizens of the United States, residing at Syracuse, in the county of 5 Onondaga and State of New York, have invented new and useful Improvements in Drying Apparatus, of which the following is a specification.

This invention relates to that class of drying-machines which are used for drying liquid and semiliquid materials and which embody one or two hollow steam-heated cylinders which are arranged horizontally and are slowly rotated and which receive the liquid material to be dried on the lower portion of 10 their outer surface and elevate the material in a thin layer or coating and carry the same over to the opposite side of the cylinder, where the material which has become dry during its movement with the cylinder is removed by a scraper.

This invention has the object to produce a drier of this general character which is suitable for drying liquid or semiliquid materials 15 which are not sufficiently adhesive to permit of their being picked up by the cylinder and elevated for the purpose of distributing the materials in a thin layer over the surface of the drying-cylinder.

In the accompanying drawings, consisting of three sheets, Figure 1 is a top plan view of a drying-machine embodying our improvements and having the drying-cylinders arranged side by side. Fig. 2 is a vertical longitudinal sectional elevation approximately in line 2 2, Fig. 1. Fig. 3 is an end elevation of the machine, partly in section. Fig. 4 is a vertical cross-section thereof in line 4 4, Fig. 1. Fig. 5 is a detached sectional view, 20 on an enlarged scale, of one corner of the feed-box. Fig. 6 is a horizontal section, on an enlarged scale, of one of the scrapers which clean the ends of the drying-cylinders. Fig. 7 is a side elevation thereof. Fig. 8 is a sectional elevation showing an apparatus in which the drying-cylinders are arranged one above the other.

Like letters of reference refer to like parts in the several figures.

50 A A' represent two drying-cylinders which are arranged horizontally and side by side in

such near proximity that the space between the cylinders is very narrow and just sufficiently wide to form a feed-opening for supplying the liquid or semiliquid material to be 55 dried to the surface of both cylinders. One of these cylinders is mounted in fixed bearings b, which are secured to the stationary end frames B, and the other in bearings b', which are adjustable on said frames toward 60 and from the bearings b by screws b² or other suitable means, so that the width of the space between the cylinders can be nicely adjusted. Both cylinders may, however, be mounted in adjustable bearings, if desired. These cylinders are hollow and are heated, as usual, by steam, which is admitted to each cylinder through the hollow front gudgeon C by a pipe c at the front end of the cylinder, while the water of condensation drains off by a pipe c' 70 at the opposite end through the hollow rear gudgeon C'. Any other suitable means for heating the cylinders may, however, be employed. These cylinders are slowly rotated by any suitable mechanism in such directions that their adjacent or opposing portions move downwardly, as indicated by the arrows in Fig. 4. The mechanism shown for that purpose in the drawings is constructed as follows:

d represents a horizontal driving-shaft arranged parallel with the cylinders on the front side of the machine and provided with tight and loose pulleys D D'. This shaft transmits motion to an intermediate shaft e by a pinion 85 E and gear-wheel E'. From the intermediate shaft the motion is transmitted to the front gudgeon C of the first cylinder A by a pinion e' and gear-wheel E². The latter meshes with a gear-wheel E³ on the front gudgeon of the 90 second cylinder A'.

F represents the feed box or receptacle which contains the liquid or semiliquid material to be dried and which is arranged over the adjacent portions of the cylinders. This 95 receptacle, as shown, consists of side boards f, which are arranged lengthwise of the cylinders, and end boards f', which are arranged against the ends of the cylinders. Each side board f is arranged over the descending upper portion of one of the cylinders and is secured by bolts to a longitudinal angle-bar 100

g, forming part of the stationary frame and secured at its ends to the end frames *B*. The lower end of each side board is fitted more or less snugly against the surface of the cylinder. Each end board is fitted against the ends of both cylinders with a sufficient lap, as indicated in Fig. 2, to form a practically tight joint and is pressed against the ends of the cylinders by adjusting-screws *g'*, which are arranged in the end frames *B* and bear against metallic wear-plates *g²* on the outer side of each end board. The end boards are fitted between the side boards *f* and are connected with the same, preferably, by screws *h*, which pass through longitudinal slots *h' h²* in the side boards and in the angle-bars *g* and are tapped into the end boards. Upon loosening these bolts the end boards can be pressed against the cylinders, and when the end boards have been so adjusted to the cylinders a tight joint is formed between the end boards and side boards by tightening the bolts *h*. The side boards may, however, be omitted, as the space between the cylinders is ordinarily not filled so high that the liquid material reaches the side boards. The latter are used principally to prevent splashing of the material and less to confine the body of the material. The end boards may be arranged between the converging surfaces of the cylinders instead of against the ends of the cylinders, if preferred.

I represents a stirrer or agitator which is arranged in the feed-box for breaking up the material adjacent to the surface of the cylinders. The upper descending portions of the latter practically form the bottom of the feed-box, and as their surfaces are very hot bubbles of steam or vapor are generated, which cover their surfaces and prevent the liquid material from coming in direct contact with the heated surfaces and adhering thereto. This stirrer or agitator breaks up these bubbles and causes the material to coat the descending portions of the cylinders and pass downwardly in a thin film or layer, which becomes divided, as the cylinder-surfaces separate, into two films or layers, one adhering to each cylinder. This stirrer may be constructed in various ways, but is preferably constructed as follows:

i represents a reciprocating rod arranged lengthwise over both cylinders and guided in bearings *i'* of any suitable construction in the end boards of the feed-hopper. *J* represents stirrer blades or arms, which are arranged at right angles to the rod *i'* and secured with their upper portions to this rod. The lower portion of each blade conforms to the curvature of both cylinders and has two downwardly-converging concave edges *j*, which are arranged as closely to the surface of the cylinders as practicable without actually touching the same. The tips or lower ends of the several blades *J* are preferably stiffened by a longitudinal stay-rod *j'*. This stirrer is slowly reciprocated in the feed-box

by any suitable mechanism. That which is shown in the drawings is constructed as follows:

K represents a crank-wheel mounted on a horizontal transverse shaft *k* in front of the feed-hopper and having its pin *k'* engaged in a depending fork *k²*, secured to the front end of the stirrer-rod, so that the rotatory movement of the crank-pin produces a reciprocating movement of the stirrer-rod. The shaft *k*, on which the crank-wheel is mounted, is driven from a transverse shaft *l* below by a chain belt *l'*, running around wheels *l² l³*. The transverse shaft *l* is driven from a longitudinal counter-shaft *m* by a pair of bevel gear-wheels *m' m²*, and the counter-shaft receives its motion from the gear-wheel *E³* of the second cylinder *A'* by a pinion *m³*, meshing with said gear-wheel.

N represents the scraper, which is arranged over the ascending upper portion of each cylinder and which removes the dried material from the surface of the cylinder. These surface-scrappers may be constructed in any ordinary or suitable manner. As shown in the drawings, they consist each of a scraper-blade *n*, which is adjustably secured to a holder *n'*, pivoted by longitudinally-arranged journals *n²* in bearings *n³*, arranged on standards *n⁴*, secured to the end frames *B*. By turning the holder in its bearings the inclination of the scraper-blade is adjusted, and the holder is secured in its adjusted position by clamping-screws *o*, passing through wings *o'* on the holder and through curved slots *o²* in the standards *n⁴*.

P represents end scrapers, one of which bears against each end rim *p* of each cylinder and keeps the end clear, so that no accumulation of material takes place at the ends, which would interfere with the snug fit of the end boards of the feed-box against the cylinder. The preferred construction of these end scrapers is shown in Figs. 2, 6, and 7, in which the inner portion of the scraper-blade *P* is inclined against the direction in which the cylinder rotates, as indicated by the arrow in Fig. 6, and secured with its flat or square shank to an ear *Q* of the stationary frame. The blade is adjusted toward and from the cylinder by a screw *q* and secured to the ear *Q* by a bolt *q'*, which passes through a slot *q²* in the shank of the blade.

The liquid or semiliquid material to be dried, which may be, for instance, a liquid food preparation, is placed in the feed-box or on the cylinders between the end boards and rests on the upper descending portions of the drying-cylinders which heat the material. The surfaces of these cylinders become coated with this material, and as the surfaces approach each other in moving toward and through the line of closest proximity a pressure is exerted upon the material which causes the same to adhere to these surfaces. The cylinders are so adjusted with reference to each other that this pressure is sufficient

to properly coat the cylinders and cause the coating to be divided into two layers or films of the proper thickness below the line of closest proximity, where the surfaces of the 5 cylinders diverge downwardly. The speed of the cylinders is, as usual in such machines, such that the layers or films of material which adhere to the cylinder-surfaces have become thoroughly dry when they reach the surface-scrapers. The latter remove the dried material from the cylinders in the form of thin broken sheets, flakes, or powder, as usual, and the removed material drops down on the ascending sides of the cylinders and is collected 15 in receptacles R.

Our improved drying-machine is suitable for drying liquid or semiliquid materials of various kinds and is particularly advantageous for drying liquid materials which are 20 not sufficiently adhesive to be elevated by the drying-cylinder from a trough or receptacle facing the lower ascending portion of the cylinder, which is the arrangement ordinarily employed in drying-machines of this general 25 character.

While our improved machine is more particularly designed for use as a drier, it is also capable of other uses—for instance, as a cooler for lard and like substances—in which case a 30 cooling medium is caused to flow through the cylinders.

For the sake of brevity we designate the apparatus as a "drying" apparatus and the cylinders as "drying-cylinders;" but we wish 35 to be understood as covering by that designation any other use for which the apparatus can be employed.

The drying-cylinders may be arranged one above the other, as shown in Fig. 8, instead 40 of side by side. In this modified construction the feed-receptacle is arranged on one side of the apparatus and against the converging or approaching surfaces of the cylinders A² A³, so that the material rests against 45 the same and upon the bottom S of the feed-receptacle, which bottom fits snugly against the surface of the lower cylinder A³. s s' represent the surface-scrapers whereby the dried 50 material is removed from the cylinders, and which are arranged, respectively, above and below the feed-receptacle.

We claim as our invention—

1. In a drying apparatus, the combination with two opposing drying-cylinders and 55 means whereby said cylinders are rotated with their opposing surfaces downwardly, of a feed-inclosure for the liquid or semiliquid material to be dried, fitted tightly against the upper descending portions of both cylinders, 60 which portions support the material in said inclosure, and means whereby the dried material is removed from the cylinders, substantially as set forth.

2. In a drying apparatus, the combination 65 with two opposing drying-cylinders and means whereby said cylinders are rotated with their opposing surfaces downwardly, of

end boards which close the downwardly-converging space between the upper descending portions of both cylinders and receive the 70 liquid or semiliquid material to be dried between them, confining the body of said material upon the upper descending portions of both cylinders, from which said material escapes through the space between both cylinders, substantially as set forth. 75

3. The combination with two opposing drying-cylinders and means whereby said cylinders are caused to rotate with their opposing surfaces in the same direction, of a feed-receptacle having end boards which are arranged 80 against the cylinders and inclose the space between the converging portions of the same, substantially as set forth.

4. The combination with two opposing drying-cylinders, means whereby said cylinders are caused to rotate with their opposing surfaces downwardly, and the stationary frame in which said cylinders are mounted, of a feed-receptacle having end boards which are arranged 85 against the ends of said cylinders and which close the space between the upper descending portions of the cylinders at the ends thereof, and adjusting devices mounted on said stationary frame and pressing the end 90 boards against the ends of said cylinders, substantially as set forth. 95

5. The combination with two opposing drying-cylinders and means whereby said cylinders are caused to rotate with their opposing surfaces downwardly, of a feed-receptacle 100 composed of side boards arranged lengthwise over the descending upper portions of said cylinders and end boards arranged against the ends of said cylinders, substantially as set 105 forth.

6. The combination with two opposing drying-cylinders, means whereby said cylinders are caused to rotate with their opposing surfaces downwardly, and the stationary frame 110 in which said cylinders are mounted, of a feed-receptacle composed of side boards which are arranged lengthwise over the descending upper portions of said cylinders and are secured to said stationary frame and end boards 115 which are arranged against the ends of the cylinders and between the side boards, adjusting-screws arranged in the stationary frame and pressing said end boards against the cylinders, and screws connecting the end 120 boards with the side boards and passing through longitudinal slots in the side boards, substantially as set forth.

7. In a drying apparatus, the combination with two opposing drying-cylinders and 125 means whereby said cylinders are rotated with their opposing surfaces downwardly, of a feed-receptacle for the liquid or semiliquid fitted against the upper descending portions of both cylinders and confining the material upon the 130 same, a stirrer arranged in said receptacle near the surfaces of said cylinders, and mechanism whereby said stirrer is actuated, substantially as set forth.

8. The combination with two opposing horizontal cylinders, means whereby the same are rotated with their opposing surfaces in the same direction and a feed-receptacle arranged 5 against the converging or approaching surfaces of said cylinders, of a horizontal reciprocating rod and converging stirrer-blades secured to said rod and projecting into the converging space between the approaching surfaces of the cylinders, substantially as set forth.

9. The combination with two opposing drying-cylinders and means whereby said cylinders are caused to rotate with the opposing 15 surfaces in the same direction, of a feed-re-

ceptacle having end boards which are arranged against the ends of both cylinders and close the space between the approaching or converging portions of the cylinders at the ends thereof, and end scrapers which bear 20 against the ends of said cylinders, substantially as set forth.

Witness our hands this 10th day of September, 1898.
